UNITED STATES PATENT OFFICE

141,745

DESIGN FOR A TOY ROLLER

William Smith, New York, N. Y.

Application March 28, 1945, Serial No. 118,749

Term of patent 14 years

(Cl. D34—15)

To all whom it may concern:

Be it known that I, William Smith, a citizen of the United States, residing at New York, county and State of New York, have invented a new, original, and ornamental Design for Toy Roller, of which the following is a specification, reference being had to the accompanying drawing, forming part thereof.

Figure 1 is a plan view.

I claim:

The ornamental design for a toy roller, as shown.

WILLIAM SMITH.
